United States Patent Office

Des. 223,880
Patented June 13, 1972

223,880

COMB

James Edgar Tucker, Chicago, Ill., assignor to The Gillette Company, Boston, Mass.

Filed Nov. 16, 1970, Ser. No. 26,023

Term of patent 14 years

Int. Cl. D28—03

U.S. Cl. D86—8

FIG 2

FIG 5

FIG 6

FIG 8

FIG. 1 is a side elevational view of a comb showing my new design;

FIG. 2 is a top plan view thereof;

FIG. 3 is a bottom plan view thereof;

FIG. 4 is an end view taken along line 4—4 of FIG. 3;

FIG. 5 is a cross-sectional view taken on line 5—5 of FIG. 3;

FIG. 6 is a cross-sectional view taken on line 6—6 of FIG. 3;

FIG. 7 is a cross-sectional view taken on line 7—7 of FIG. 3;

FIG. 8 is a cross-sectional view taken on line 8—8 of FIG. 3.

I claim:

The ornamental design for a comb, as shown.
